UNITED STATES PATENT OFFICE.

HENRY H. HENDERSON, OF NEW GLASGOW, NOVA SCOTIA.

STORE-COUNTER.

SPECIFICATION forming part of Letters Patent No. 224,429, dated February 10, 1880.

Application filed May 23, 1879.

To all whom it may concern:

Be it known that I, HENRY H. HENDERSON, of New Glasgow, Nova Scotia, have invented an Improvement in Sectional Store-Counters, 5 of which the following is a specification.

The invention relates to means for supporting the hinged covers of the sections; and it consists in two jointed bars or rods, one pivoted on the inside and the other provided with 10 an end eye that slides on a keeper attached to the under side of the cover, in combination with a notched cam on the inside of one end of the section, so that the pivoted rod catches behind the shoulder when the cover is opened 15 and holds it firmly in position.

Figure 1 of the drawings is a vertical longitudinal section; Fig. 2, a vertical cross-section.

In the drawings, A represents a counter-section forming a close box, on wheels, and a the 20 cover, which is hinged so as to be swung back.

b b' are two rods or bars jointed together, the former being pivoted to one of the sides, and the latter having an end eye through which passes the keeper *a'* on the bottom of the cover. 25 *c'* is a cam which gradually rises and suddenly ceases altogether, so as to form a shoulder behind which the rod *b* passes as soon as the cover is thrown back, and securely retains it in position. 30

What I claim as new and of my invention is—

The hinged cover of a sectional counter, provided on its under side with a keeper, *a'*, in combination with a notched cam, *c'*, at one end 35 of box-section and the jointed rods *b b'*, the rod *b'* having an end eye that slides on keeper, as shown and described.

HENRY HARTLEY HENDERSON.
